Patented Jan. 9, 1962

192,032

RIFLE

Eugene M. Stoner, Newport Beach, Calif., assignor to
Fairchild Engine and Airplane Corporation, Hagers-
town, Md., a corporation of Maryland

Filed Mar. 15, 1960, Ser. No. 59,742

Term of patent 14 years

(Cl. D30—1)

FIG. 1 is a side elevational view of a rifle showing my new design;

FIG. 2 is a side elevational view opposite to the side shown in FIG. 1;

FIG. 3 is a top plan view;

FIG. 4 is a bottom plan view;

FIG. 5 is a front end elevational view; and

FIG. 6 is a rear end elevational view.

The characteristic features of the design for the rifle disclosed reside in the area comprising the magazine, receiver and trigger portion having the configuration shown.

FIG. 6.

FIG. 5.

I claim:
The ornamental design for a rifle, as shown and described.
